UNITED STATES PATENT OFFICE.

ERBERTO DURIO, OF TURIN, ITALY.

MACHINE FOR STRETCHING TANNED SKINS AND LEATHERS.

1,367,028.

Specification of Letters Patent. Patented Feb. 1, 1921.

Application filed February 10, 1920. Serial No. 357,584.

To all whom it may concern:

Be it known that I, ERBERTO DURIO, a subject of the King of Italy, and resident of Tarin, Italy, have invented certain new and useful Improvements in Machines for Stretching Tanned Skins and Leathers, of which the following is a specification.

It is known that certain tanned skins and leathers of given classes must be subjected to a stretching operation before being put in use, for the purpose of preventing their further elongation when used, say, as driving belts and the like.

For obtaining satisfactory results it is necessary that the stress exerted on the skin to be stretched has not the same value on the whole width of the skin, but on the contrary the value of the stretching stress must be proportional to the yieldingness (that is, to the liability to be elongated) of each zone or portion of the skin; as it is known, the character of the skin as to yieldingness is quite different in several zones of the skin, being lower in the middle portion of the skin 25 and higher in the side and end portions.

This invention has for its object a machine for stretching skins and leathers in which each of the opposite edges of the skin to be stretched is grasped by a row of nippers, the nippers of each row being adjacent to and independent of each other; the nippers of one of the rows are then moved away from those of the other row by an operative force, say a fluid pressure, 35 which acts on all said nippers with the same intensity so that the several portions of the skin are elongated to different extents on account of their different yieldingness.

This invention comprises also particular constructions of the nippers as well as the mounting in a resilient manner of the nippers which are not operated by means adapted to produce the stretching action.

The annexed drawing shows by way of example an embodiment of this invention and in the same Figure 1 is a vertical section of the machine on line α — α , Fig. 2, and Fig. 2 is a plan view.

As shown in the drawing, on a base plate 50 or frame 1, which is supported by stands or legs 2, are mounted two rows of nippers 3 and 3', arranged side by side, each row being located near one of the ends of said plate or frame 1.

Each of the nippers comprises two jaws 55 pivoted at 4' and having their tails 5 con-

nected with a rod 6 by means of links 7 so that said jaws act to grasp the material when a pull is exerted on rod 6.

The nippers of one of the rows as 3 may 60 be stationary on the base plate or frame but it is preferable to mount the same in a spring or resilient manner.

Such a mounting may be effected, as in the embodiment shown on the drawing, by 65 means of a bar 10 extending across the plate 1 and through which the rods 6 of the several nippers freely pass; on each rod 6 is arranged a spring 8 bearing against said bar and a head 9 adjustably mounted on the end 70 of rod 6, so that the springs may be adjusted independently of each other.

Said bar 10 is connected by means of standards 19 passing through suitable slots 18 in plate 1, with a bar 20 located under the 75 plate 1 and having nuts engaged by screw-threaded spindles 16 operated at the same time and to the same extent by means of pinions 17 meshing with each other.

Of course the bar 10 may be stationary on 80 plate 1, the described device being omitted.

The nippers 3' of the row located at the opposite end of the plate 1 are similar to those above described and each of them has its rod 6 connected with a piston 6' sliding 85 in a cylinder 11.

Each cylinder is mounted on the base plate 1 so as to be free to swing around an axis perpendicular to plate 1 and to move along said plate in a transverse direction. 90 This mounting is obtained by means of a journal or pivot 12 fixed to the cylinder and engaged in a slot 13 extending the entire width of the plate 1; said journal 12 is conveniently provided with a screw 95 threaded end portion on which is located a nut 14 enabling the cylinder to be locked at the required place.

For improving the mounting of the cylinders a bar may be provided above them, 100 said bar being connected with the plate 1 and having a slot entered by a journal similar to the journals 12 above described.

The end of each cylinder in front of the associated nippers 3' is connected with a 105 pipe 15 to which may be fed a fluid under pressure.

The operation is as follows: The opposite edges of the skin or leather to be stretched are engaged in nippers 3—3' and a fluid 110 under pressure is fed to pipe 15; therefore the fluid pressure acts in an independent

manner in each cylinder 11 on the associated piston 6' so that the strokes made by each piston and the nippers connected with it are different on account of the different yieldingness of the zones of the skin engaged by said nippers, the pressure being equal in the several cylinders.

By spring mounting the nippers of the stationary row the displacement of the same 10 may be adjusted within certain ranges according to requirements by adjusting each spring 8 as above described.

Further by moving bar 10 carrying the stationary nippers the machine may be applied to skins and leathers having different sizes.

The machine according to this invention enables the stretching of the skins and leathers in all their zones or portions to the 20 extent required for preventing their further elongation.

I claim as my invention:—

1. A machine for stretching tanned skins and leathers comprising a frame, a plurality 25 of grasping members independent of each other arranged in a row and connected with said frame, a plurality of cylinders connected with said frame and arranged in a row, a piston in each cylinder, a plurality of 30 grasping means independent of each other and each connected with one of said pistons, the grasping means of each row being adapted to engage one of the opposite edges of the skin or leather, and means for feeding 35 a fluid under pressure into said cylinders, said feeding means opening into all said cylinders.

2. A machine for stretching tanned skins and leathers comprising a frame, a plurality 40 of grasping members independent of each other arranged in a row and connected with said frame, a plurality of cylinders arranged in a row, means connecting said cylinders with said frame and allowing said cylinders 45 to swing and move freely in a transverse direction on said frame, a piston in each cylinder, a plurality of grasping means independent of each other and each connected with one of said pistons, the grasping means 50 of each row being adapted to engage one of the opposite edges of the skin or leather, and means for feeding a fluid under pressure into said cylinders, said feeding means opening 55 into all said cylinders.

3. A machine for stretching tanned skins and leathers comprising a frame, a plurality 60 of grasping members independent of each other arranged in a row and connected with said frame, a plurality of cylinders arranged in a row, a slot in said frame, means on said cylinders engaging said slot to allow said cylinders to swing and move freely along 65 said slot, means for locking said cylinders in position, a piston in each cylinder, a plurality of grasping members independent of

each other and each connected with one of said pistons, the grasping members of each row being adapted to engage one of the opposite edges of the skin or leather, and means for feeding a fluid under pressure into said cylinders, said feeding means opening into all said cylinders.

4. A machine for stretching tanned skins and leathers comprising a frame, a plurality 75 of cylinders connected with said frame and arranged in a row, a piston in each cylinder, a plurality of grasping members independent of each other and each connected with one of said pistons, means for feeding a fluid under pressure into said cylinders, 80 said feeding means opening into all said cylinders, a plurality of grasping members independent of each other and arranged in a row, and adjustable spring means connecting each of the last named grasping 85 members with said frame, the grasping members of each row being adapted to grasp one of the opposite edges of the skin or leather.

5. A machine for stretching tanned skins 90 and leathers comprising a frame, a plurality of cylinders connected with said frame and arranged in a row, a piston in each cylinder, a plurality of grasping members independent of each other and each connected with 95 one of said pistons, means for feeding a fluid under pressure into said cylinders, said feeding means opening into all said cylinders, a plurality of grasping members independent of each other and arranged in a 100 row, a part connected with said frame, each of the last named grasping members being snugly engaged with said part, and adjustable spring means between said part and each of the associated grasping members, 105 the grasping members of each row being adapted to engage one of the opposite edges of the skin or leather.

6. A machine for stretching tanned skins and leathers comprising a frame, a plurality 110 of cylinders connected with said frame and arranged in a row, a piston in each cylinder, a plurality of grasping members independent of each other and each connected with one of said pistons, means for feeding a 115 fluid under pressure into said cylinders, said feeding means opening into all said cylinders, a plurality of grasping members independent of each other and arranged in a row, a part mounted to move on said frame, each of the last named grasping members being snugly engaged with said part, adjustable spring means between said part and each of the associated grasping members, and means for shifting said part along said 120 frame, the grasping members of each row being adapted to engage one of the opposite edges of the skin or leather.

7. A machine for stretching tanned skins and leathers comprising a frame, a plurality 130

of grasping members independent of each other arranged in two rows at the sides of said frame, the grasping members of each row being adapted to engage one of the opposite edges of the skin or leather, a plurality of cylinders connected with said frame, a piston in each cylinder, each piston being connected with one of said grasping members for operating it, and means

for feeding a fluid under pressure into said cylinders to drive said pistons, said feeding means opening into all said cylinders, each of said grasping members comprising jaws pivoted together and links connecting said jaws with a rod fixed to the associated piston.

Signed at Turin, Italy, January 9, 1920.
ERBERTO DURIO.
